UNITED STATES PATENT OFFICE

165,230

TOY AIRPLANE

Frank W. Kertell, Oakland, Calif.

Application October 21, 1949, Serial No. 5,620

Term of patent 7 years

(Cl. D34—15)

To all whom it may concern:

Be it known that I, Frank W. Kertell, a citizen of the United States, and a resident of Oakland, Alameda County, California, have invented a new, original, and ornamental Design for a Toy Airplane, of which the following is a specification, reference being had to the accompanying drawing, forming part thereof.

Figure 1 is a right perspective view of a toy airplane, showing my new design;

Figure 2 is a left perspective view thereof; and

Figure 3 is a bottom perspective view thereof.

The fragmentary dotted line showing of a tethering string in Fig. 3 is for illustrative purposes only.

I claim:

The ornamental design for a toy airplane, substantially as shown and described.

FRANK W. KERTELL.
